PAINT SPRAY MACHINE

Edward O. Norris, Westport, Conn.

Application June 29, 1945, Serial No. 602,272

9 Claims. (Cl. 299—63)

1

This invention relates to centrifugal spraying devices and more particularly to a light weight, portable sprayer suitable for spraying paint or other liquids onto a surface.

An object is to provide a simple, compact, light weight device of the above type which is suited to general use by relatively unskilled labor or by amateur painters.

Another object is to provide a painting device having novel and improved features of construction and operating characteristics.

Various other objects and advantages will be apparent as the nature of the invention is more fully disclosed.

In accordance with the present invention, I provide a centrifugal distributor having a plurality of annular passages through which the liquid is ejected and arranged to provide a uniform spray of substantial thickness.

The liquid to be sprayed is held in a closed supply reservoir located above the level of the distributor and flows to the distributor by gravity. A stationary casing surrounds the distributor and is provided with an opening of adjustable width through which the spray passes. The liquid intercepted and collected by the casing flows by gravity to a receiver located below the level of the distributor. The reservoir is provided with an air vent which is arranged to be cut off by the rising level of the liquid in the receiver so as to interrupt the feed when the receiver is filled to its capacity. The collected liquid is then returned from the receiver to the supply reservoir by inverting the device for an instant. In normal use this occurs automatically at frequent intervals as the device is laid down or the hand is lowered between spray shots.

The invention further provides a releasable shield over the front of the distributor which is controlled by the operating trigger to prevent drip or drift of spray when the supply is interrupted, thereby providing a sharp cut-off and accurate control.

A motor driven fan is also provided to draw air through the spray opening counter to the flow of spray in a manner to remove mist and leave a clean spray free from fine particles which would otherwise be dispersed in the air.

Although the various novel features which are believed to be characteristic of this invention are pointed out more particularly in the claims appended hereto, the invention will be better understood by referring to the following description taken in connection with the accompanying

2

drawings in which a specific embodiment thereof has been set forth for purposes of illustration.

In the drawings:

Fig. 1 is a side elevation partly in section taken on the line 1—1 of Fig. 2 showing a spraying device embodying the present invention;

Fig. 2 is a section taken on the line 2—2 of Fig. 1;

Fig. 3 is a detail view of the control linkage for the feed and shield;

Fig. 4 is a central vertical section through the receiver and a portion of the reservoir with the centrifugal distributor removed;

Fig. 5 is a side elevation of the driving motor, fan and distributor removed from the casing;

Fig. 6 is a section taken on the line 6—6 of Fig. 5; and

Fig. 7 is a top plan view of the distributor.

Referring first to Figs. 1 and 4, the spraying device is shown as comprising a housing 10 having an intermediate partition 11 dividing the housing into an upper supply reservoir 12 and a lower receiver 14. A filler cap 15, shown as threaded, is provided at the upper part of the housing 10 to register with a filler opening 16 through which the reservoir is filled. A gasket 21 is provided for making a tight seal.

The partition 11 is provided with an opening 22 communicating with a conical spout or feed means 23 having an aperture 20 by means of which the liquid is supplied to a centrifugal distributor 24 (Figs. 1 and 5). The opening 22 is closed by a valve 25 which is actuated by a lever 26 pivoted to a shaft 27 which carries an arm 28 (Fig. 3) connected by a pin 29 to a link 30. The pin 29 engages an elongated slot in the link 30 which provides lost motion for the purpose to be described.

The link 30 is adjustably secured to a lever 31 which is pivoted to the housing 10 and is provided with a finger control handle or trigger 32 which is in a convenient position for actuation by the operator. The lever 31 is adjustably connected to the link 30 by a pin and slot connection 33 and may be adjusted by a set screw 34 for controlling the normal position of the link. A spring 35 holds the valve 25 in closed position.

A distributor chamber 40 (Figs. 1 and 4) is formed in the receiver 14 between the partition 11 and a lower inclined partition 41 and is closed by a rear transverse partition 42. The partition 41 is provided with an opening 43 surrounded by a positioning lip 44 to receive the centrifugal distributor casing to be described. The lower end of the partition 41 adjacent the transverse parti-

tion 42 is provided with a discharge opening 45 (Figs. 1 and 2) through which liquid which is collected in the distributor chamber 46 flows into the receiver 14. The opening 45 is preferably located at one side of the chamber 46 as shown in Fig. 2.

The front of the housing between the partitions 11 and 41 is provided with a spray opening defined by an inturned top flange 48 (Figs. 1 and 4) and an inturned bottom flange 49 and inturned side flanges 50 and 51 (Fig. 2). The inturned flanges 48 and 49, 50 and 51 form pockets to prevent any liquid which has collected in the distributor chamber from flowing out of the spray opening when the device is tilted.

In order to vary the width of the spray opening a pair of slides 52 and 53 (Fig. 2) are mounted at opposite sides of the opening to slide in channels formed by flanges 54 secured to the lower partition 41 and flanges 55 secured to the upper partition 11. Control handles 56 and 57 are attached to the slides 52 and 53, respectively, and project beyond the front of the housing 10 into an accessible position. These control handles are arranged to flare outwardly at about the spray angle and, in their retracted position, to lie against the inturned flanges 50 and 51 of the housing.

A return and vent passage, shown as a tube 60, is provided for returning the liquid from the receiver 14 to the supply reservoir 12. This tube 60 communicates with an opening 61 in the partition 11 which is located at the side of the receiver opposite the opening 45. The tube 60 extends to the upper part of the reservoir 12 at a point above the normal liquid level in the reservoir and removed from the filler opening 16 so that the liquid does not enter the tube 60 when the reservoir is being filled through the opening 16. The tube 60 serves both as an air vent for the reservoir 12 and as a return passage for the liquid as will be described.

Referring now to Figs. 1 and 5, the centrifugal distributor 24 is shown as comprising a plurality of superposed frustro-conical rings 65 having peripheral upturned lips 66. These rings 65 are stacked and secured by means of spacing posts 67 to a conical ring member 70 which is mounted by arms 68 upon a shaft 71 of an electric motor 72. The conical surface of the ring member 70 causes any liquid retained in the distributor when the motor is stopped to drain out through the passages between the rings 65. A plurality of superposed conical screens 74 are mounted on the shaft 71 to extend over the central opening in the ring member 70.

A two-stage impeller comprising vanes 76 and 77 (Fig. 1) is also mounted on the shaft 71 in a position to draw air in through the spray opening and screen 74 and to discharge the same downwardly through a fan housing 78, then around baffles 79 and 80 and into the atmosphere above the motor 72. The screens 74 provide a rotating surface which impels the liquid outwardly and prevents the liquid from being drawn downwardly with the air flow induced by the impeller. The housing 78 is spaced from the motor 72 by struts 81 to provide an air discharge opening and carries a band 84 which fits within the lip 44 of the housing 10. The housing 78 is provided with threads 82 to engage a threaded flange 83 carried on the housing 10.

A shield 85 (Figs. 1 and 2) extends around the distributor 24 and between the distributor and the spray opening and is attached to a rod 86

which is pivoted in the housing 10 and carries an actuating cam 87 (Fig. 3) having a shoulder 88 which is positioned to engage a shoulder 89 formed on the link 30. The spring 35 normally holds the shoulder 88 against the shoulder 89 of the cam 87 to hold the shield 85 in position to intercept any spray being ejected from the distributor as indicated in Fig. 1. When the handle 32 is actuated toward the motor 72 the link 30 is moved to the right as shown in Fig. 3, allowing the shield 85 to drop by gravity and also opening the valve 25. Release of the handle 32 allows the spring 35 to return the link 30 to its original position, closing the valve 25 and raising the shield 85 to cut-off position. The lost motion pin and slot connection 29 permits the shield 85 to drop before the valve 25 opens and also allows the valve 25 to close before the shield 85 is elevated. The shield 85 also fails to cut off position by gravity if the machine should be tilted to an angle such that normal gravity feed of liquid to the distributor does not take place.

The motor 72 is provided with a housing of suitable size to provide a handle and support for the device so that in normal operation the device is held by grasping the motor housing in the hand with the handle 32 in a position to be actuated by the fingers.

The motor is of standard construction and is designed to draw cooling air upwardly into its housing due to its rotation. In order to prevent dust from being drawn into the motor 72 with the cooling air, the motor housing is extended to provide a circular casing 90 which is adapted to receive a filter pad 91 which may be supported by screens 92 and 93 located on opposite sides thereof. The screen 92 is shown seated against a flange 94 formed on the interior of the casing 90 and the screen 93 is positioned by a split ring 95 which is secured in an annular recess 96 formed in the casing 90. In this way the filter material 91 can be readily removed for cleaning or replacement. The casing 90 may be removably attached to the motor housing as by bayonet slots 97 (Fig. 5).

In the operation of this device, the reservoir 12 is first filled with the liquid to be sprayed by removing the filler cap 15. When this filler cap is replaced, the reservoir 12 is closed except for the outlet passage 22 through which the liquid is supplied to the centrifugal distributor 24 and the air vent which includes the tube 60, the opening 61, the receiver 14, the opening 45, the distributor chamber and the spray opening in the housing 10. The valve 25 is normally held closed by the spring 35 and the shield 85 is normally held in elevated position in alignment with the distributor to prevent ejection of the liquid through the spray opening. For spraying, the motor is started and the handle 32 is actuated toward the motor 72, thereby releasing the shield 85 and allowing it to drop out of registration with the distributor and also opening the valve 25 an amount sufficient to allow liquid to flow from the reservoir 12 through the discharge opening 22 into the distributor 24. The amount of liquid flow may be controlled by varying the position of the handle 32 to correspondingly vary the elevation of the valve member 25 and the opening therewith into the discharge passage 22. The rapidly rotating distributor 24 ejects the liquid in the form of a spray around the entire periphery thereof. It will be noted that the upwardly inclined outer flanges 66 of the distributor rings intercept any liquid which may

tend to pass directly through the passages between the rings and thereby causes all portions of the liquid to contact with a rotating surface before being ejected.

A portion of the spray passes through the spray opening as indicated in Fig. 2, the remainder being caught in the distributor chamber and flowing downwardly along the sloping partition 41 and through the opening 45 into the receiver 14. This action continues until the level of the liquid in the receiver 14 rises sufficiently to cut off the opening 45 and thereby prevents further entrance of air into the reservoir 12. When this occurs the air pressure in the reservoir 12 becomes insufficient to cause further flow of liquid through the opening 22 and the spray ceases, thereby indicating that the receiver 14 has been filled with the collected liquid. The receiver 14 is then emptied by tilting the device over on its side far enough to permit the liquid to flow through the opening 61 and tube 60 into the reservoir 12. Of course the handle 32 should be pulled toward the motor 72 while the machine is inverted so as to open the valve 25 and permit passage of air. However, no liquid will be sprayed because the shield 85 falls into shutoff position. When the liquid has thus been returned from the receiver 14 into the reservoir 12 the device is ready for further operation.

In normal operation the device is laid down or the hand lowered between spray shots at sufficiently frequent intervals to take care of the return of the liquid from the receiver 14 to the reservoir 12 automatically.

When it is desired to stop the spray, the handle 32 is released, whereupon the spring 35 rotates the shaft 27 to close the valve 25 and retracts the link 30, bringing the shoulder 88 of the link 30 into engagement with the shoulder 88 of the cam 87 and rotating the cam 87 to restore the shield 85 to its cut-off position. It will be noted that when the cam 87 is released by actuation of the handle 32 the cam only rotates a limited amount as the housing 78 serves as a stop to limit the movement of the shield 85. Hence the shoulders 88 and 89 remain in registration regardless of the amount of movement of the link 38 after the cam 87 has been released. The lost motion connection permits the valve 25 to close first so that the liquid in the distributor 24 may be ejected therefrom before the shield 85 is brought into intercepting position. Thereafter no further emission of spray is possible even though the valve 25 should fail to close tightly.

The width of the spray may be adjusted by varying the position of the slides 52 and 53 by means of the handles 56 and 57. The spray may thus be varied from a maximum width to a narrow stripe, as may be required for the particular operation in hand.

It will be noted that the above device is gravity fed and that the unused liquid is likewise returned by gravity to the reservoir, thereby eliminating all mechanical feed mechanisms. Furthermore, the device is capable of operation at any angle at which flow of liquid may be had from the reservoir 12 through the supply passage 22. At other angles, such as when the device is inverted for returning the liquid from the receiver 14, the shield 85 automatically falls to the cut-off position, thereby preventing accidental ejection of spray.

The fans 76 and 77 aid in obtaining a clean spray by removing the fine particles therefrom.

It is to be understood, however, that if this feature is not required, the fan mechanism may be omitted, and the motor 72 mounted directly within the housing 78. In that event, the motor 72 of Fig. 1 will be replaced by an operating handle.

While in normal position, the liquid flows down the inclined partition 41 and through the opening 45 into the receiver 14, the inturned flanges 10 48 and 49 prevent any liquid collected within the distributor chamber from flowing outwardly through the spray opening when the device is inclined in other positions.

Although a specific embodiment of the invention has been shown for purposes of illustration, it will be understood that the invention is capable of various uses and that suitable changes and modifications may be made therein as will be readily apparent to a person skilled in the art. The invention is only to be restricted in accordance with the scope of the following claims.

What is claimed is:

1. A centrifugal spraying device comprising a centrifugal distributor, a closed liquid reservoir mounted above said distributor, gravity feed means including a port in said reservoir connected to supply liquid for spraying to said distributor, a casing surrounding said distributor to intercept and collect the liquid ejected therefrom and having a spray opening to pass a selected portion of the spray, a receiver mounted below said distributor, said casing having an opening positioned to drain the collected liquid by gravity into said receiver, and a passage extending from the top 30 of said receiver to a point above the liquid level in said reservoir for the gravity return of liquid from said receiver to said reservoir when the device is inverted.

2. A centrifugal spraying device comprising a centrifugal distributor, a closed liquid reservoir mounted above said distributor, gravity feed means including a port in said reservoir connected to supply liquid for spraying to said distributor, a casing surrounding said distributor to intercept and collect the liquid ejected therefrom and having a spray opening to pass a selected portion of the spray, a receiver mounted below said distributor, a passage extending from the top of said receiver to a point above the liquid level in said reservoir, said casing having an opening into said receiver below the level of said distributor to drain the collected liquid by gravity into said receiver, said opening being positioned to be closed by the liquid in said receiver to prevent further passage of air into said reservoir and thereby interrupt further gravity flow of liquid to said distributor when the liquid level reaches said opening, said passage being positioned for the return flow of liquid from said receiver to said reservoir by gravity when said device is inverted.

3. A centrifugal spraying device comprising a centrifugal distributor, a closed liquid reservoir mounted above said distributor, gravity feed means including a port in said reservoir connected to supply liquid for spraying to said distributor, a casing surrounding said distributor to intercept and collect the liquid ejected therefrom and having a spray opening to pass a selected portion of the spray, a receiver mounted below said distributor, a passage extending from one side of said receiver to a point above the liquid level in said reservoir for the passage of air to said reservoir while spraying and for the return of liquid by gravity to said reservoir when the device is in-

verted, said casing having an opening into said receiver below the level of said distributor and on the opposite side from said passage to drain the collected liquid by gravity into said receiver said opening being positioned to be closed by the liquid in said receiver, to prevent further passage of air into said reservoir and thereby interrupt further gravity flow of liquid to said distributor when the liquid level reaches said opening.

4. A centrifugal spraying device comprising a centrifugal distributor, a closed liquid reservoir mounted above said distributor, gravity feed means including a port in said reservoir connected to supply liquid for spraying to said distributor, a casing surrounding said distributor to intercept and collect the liquid ejected therefrom and having a spray opening to pass a selected portion of the spray, a receiver mounted below said distributor, a passage extending from one side of said receiver to a point above the liquid level in said reservoir for the passage of air to said reservoir while spraying and for the return of liquid by gravity to said reservoir when the device is inverted, said casing having an opening into said receiver below the level of said distributor and spaced laterally from said passage to drain the collected liquid by gravity into said receiver, said opening being positioned to be closed by the liquid in said receiver to prevent further passage of air into said reservoir and thereby interrupt further gravity flow of liquid to said distributor, a control valve for said port, and manual actuating means for said valve.

5. A centrifugal spraying device comprising a centrifugal distributor, a liquid reservoir mounted above said distributor, gravity feed means including a port in said reservoir connected to supply liquid for spraying to said distributor, a casing surrounding said distributor to intercept and collect the liquid ejected therefrom and having a spray opening to pass a selected portion of the spray, a closed receiver mounted below said distributor, said casing having an opening positioned to drain the collected liquid by gravity into said receiver, connections between said receiver and said reservoir having means for the return of liquid from said receiver to said reservoir, a housing in said receiver extending axially from said distributor, said housing being sealed to said receiver to form a closed annular chamber for retaining the liquid drained into said receiver from said casing and being open to the atmosphere at the bottom of said receiver, impeller means in said housing beyond the distributor in the direction of air flow driven with said distributor and directed to draw air around said distributor through said spray opening counter to the flow of spray for removing the fine particles from the spray and to discharge the same downwardly through said housing to the atmosphere.

6. A centrifugal spraying device comprising a centrifugal distributor, a casing having a spray opening through which a selected portion of the spray from said distributor passes, a shield interposed between said distributor and said opening, means pivotally supporting said shield to fall by gravity to retracted position for spraying, spring means holding said shield in elevated po-

sition to intercept said spray, and a manual control member connected to release said spring means.

7. A centrifugal spraying device comprising a centrifugal distributor, feed means to supply liquid thereto for spraying, a control member for said feed means, a casing having a spray opening through which a selected portion of the spray from said distributor passes, a retractable shield interposed between said distributor and said spray opening, a manual control lever, and linkage means connecting said lever to actuate both said feed control member and said shield for controlling the emission of spray.

15 8. A centrifugal spraying device comprising a centrifugal distributor, feed means to supply liquid thereto for spraying, a control member for said feed means, a casing having a spray opening through which a selected portion of the spray 20 from said distributor passes, a retractable shield interposed between said distributor and said spray opening, a manual control lever, and linkage means connecting said lever to actuate both said feed control member and said shield for controlling the emission of spray, said linkage means having a lost motion connection to said control member adapted to cause said shield to be retracted first for spraying and said feed control member to interrupt the feed by said feed means 25 first when the spraying operation is interrupted.

9. A centrifugal spraying device comprising a centrifugal distributor, a casing having a spray opening through which a selected portion of the spray from said distributor passes, means forming an air passage extending from said opening around said distributor and open at its discharge end to the atmosphere, and impeller means positioned in said passage beyond the distributor in the direction of air flow to draw air inwardly 35 around the distributor and through said spray opening counter to the flow of spray for removing the fine particles from the spray and to discharge the air through the discharge end of said passage into the atmosphere.
